ADJUSTABLE SUPPORT FOR MIRRORS

Robert C. Trainor, Pittsburgh, Pa.

Application February 24, 1950, Serial No. 146,028

1 Claim. (Cl. 248—295)

1

The present invention relates to an adjustable support for mirrors and it consists in the combinations, constructions and arrangements of parts herein described and claimed.

Generally the invention comprises a vertically extending rack adapted to be attached to a wall and provided with a longitudinally extending slot communicating with which is a series of pairs of laterally extending slots. Slidably mounted in the rack is a novel latching device carrying a mirror at one side and having novel means for selective engagement in pairs of the laterally extending slots so that the mirror may be moved upwardly from time to time to take care of the naturally increasing height of a child using the same and latched in such position until a new movement of the mirror is indicated.

It is an object of the invention to provide a device of the character set forth which is simple in construction, inexpensive to manufacture and yet effective and efficient in use.

Another object of the invention is the provision, in a device of the character set forth, of a novel latch forming a part of the invention.

A further object of the invention is the provision of a novel rack forming a part of the invention.

A still further object of the invention is the provision of novel means for supporting a mirror or the like in selected adjusted positions.

Other and further objects of the invention will become apparent from a reading of the following specification taken in conjunction with the drawings, in which

Figure 1 is a front elevational view of an embodiment of the invention,

Figure 2 is a side elevational view, partly broken away, of the device shown in Figure 1,

Figure 3 is a fragmentary sectional view taken along line 3—3 of Figure 2,

Figure 4 is an enlarged sectional view taken along line 4—4 of Figure 3, and

Figure 5 is a fragmentary exploded perspective view illustrating an adjustable clamp member and associated parts forming part of the invention.

Referring more particularly to the drawing, there is shown therein a vertically extending rack 10 having a longitudinally extending inset portion 11 in which is centrally located in a longitudinally extending slot 12 communicating with which and formed in the inset portion of which is a plurality of laterally extending pairs of slots 13.

Adjacent the upper and lower ends of the rack 10 there is affixed by means of screws 14 or the like suction cups 15 or the like whereby the rack

2

10 may be attached to a smooth surface such as is presented, for example, by a tiled wall. Of course, the invention contemplates that a rack may be directly and permanently affixed to a wall by screws, nails or other conventional means.

A mirror 16 has centrally affixed to the rear face thereof a stud 17 to which is, in turn, affixed a keystone shaped plate 18. A bracket 19 having downwardly and inwardly tapering sides 20 which are inturned to receive the sides of the plate 18, has a centrally disposed inwardly extending neck 19 to the inner end of which is integrally formed a plate 22 having a pair of rearwardly directed teeth 23 at the lower end thereof. The sides of the plate 22 are adapted to snugly and slidably fit against the sides of the inset portion 11 and the teeth 23 are selectively engageable in the pairs of slots 13.

A clamp member 24 is provided with an upper rounded portion 25, a pair of integrally formed dependent legs 26 and 27 and a pair of finger pieces 28 and 29. It will be seen that the finger pieces 28 and 29 are formed integrally with the legs 26 and 27, respectively, and that the finger piece 28 extends rearwardly and that the finger piece 29 extends forwardly. It will also be apparent that the sides of the entire clamping member 24 lie within the sides of the slot 12. Screws 31 are connected with the leg 26 through the openings 30 provided therein and through openings 30a provided in plate 22.

The leg 27 is also provided with a pair of openings, as shown at 31, and screws 32 connect the leg 27 with a guide plate 33 through the openings 31 and a pair of openings 34 which are vertically aligned in one side of the plate 33.

In operation, it will be apparent that the rack 10 may be placed upon a wall by utilizing the suction cups 15 or by permanently attaching the same to a wall by means of screws, nails or the like. Thereafter the mirror 16 may be mounted in the bracket 19 by placing the keystone shaped plate 18 therein and then adjusted to any desired height by compressing the finger pieces 28 and 29 toward each other. Such action will act upon the entire supporting mechanism for the mirror may be raised or lowered as the case may be and when it has reached a desired height the finger pieces 28 and 29 may be released whereupon the teeth 23 will again engage in the slots 13. If desired, the mirror 16 may be removed from the bracket 19 during the time that the bracket and its attendant mechanisms are raised or lowered to a new position.

While but one form of the invention has been

shown and described herein, it will be readily apparent to those skilled in the art that many minor forms thereof may be made without departing from the spirit of the invention or the scope of the appended claim.

What is claimed is:

A device of the character described comprising a vertically extending rack, an inset portion formed longitudinally in said rack and having a longitudinal slot formed therein and having a plurality of pairs of spaced relatively short laterally extending slots communicating with the longitudinal slot, means for affixing said rack to a wall, a support, and means for adjustably positioning said support in said rack, said means including a clamp member affixed to said support and vertically slidable in the longitudinal slot, teeth carried by said support and selectively engageable in said pairs of lateral slots, finger pieces carried by said clamping member for moving said teeth out of engagement with said lat-

eral slots, a rectangular plate carried by said support and slidably contacting the sides of said inset portion, and attached to one of said finger pieces, and a backing plate attached to the other of said finger pieces and adapted to bear against that side of the rack opposite to the rectangular plate.
